[57] CLAIM

The ornamental design for an air-cooled compact electric lamp, as shown and described.

DESCRIPTION

FIG. 1 is a perspective view of an air-cooled compact electric lamp embodying my new design;

FIG. 2 is a side elevational view thereof on a reduced scale, the opposite side being identical;

FIGS. 3 and 4 are top and bottom plan views, respectively, thereof on a reduced scale;

FIG. 5 is a perspective view of a second embodiment of my new design wherein air vents of modified configuration are employed at both ends and around the medial portion of the lamp;

FIG. 6 is a side elevational view thereof on a reduced scale, the opposite side being identical; and

FIGS. 7 and 8 are top and bottom plan views, respectively, thereof on a reduced scale.

FIG. 1

FIG. 3

FIG. 2

FIG. 4

FIG. 5

FIG. 7

FIG. 6

FIG. 8
